HIGH SPEED SPINNING MACHINE

Eizaburo Negishi, Kiri, Japan

Application May 1, 1937, Serial No. 140,247
In Japan May 18, 1936

9 Claims. (Cl. 118—38)

The present invention relates to high speed spinning machines provided with silver sucking devices and a rotating pot, characterized by inducing a fluid in the sucking devices to make a spiral, helical or like rotating movement with respect to the drawing mechanism or front rollers of the spinning machine. Spinning machines of centrifugal type heretofore used have been adapted to reel artificial silk threads into rotating pots, and have also been utilized directly as twisting and general spinning machines in the manner of mules or ring spinning frames. But if such machines were utilized for spinning cotton or woolen yarn, it has been found difficult to guide 5 the silver which is to be spun into the pot, and it has also been found that if the silver is broken or scattered before, or at the moment it reaches the pot, it cannot be spun. Thus for these reasons, spinning machines of the centrifugal type using 10 the pot system are not entirely practical for producing threads of these materials.

Now, according to the present invention, perfect and practical spinning is effected by passing a fluid through a guide vane to induce automatic 15 high speed rotation of the fluid therein, and then sucking the silver into said rotating fluid so as to rotate the latter, thereby giving some twist to the silver by the rotating action of the fluid to form a partly formed thread and to increase its tension 20 in order to prevent it from being broken or scattered before, or at the instant it reaches the pot.

The object of the invention is to provide a spinning machine whose efficiency is increased by 25 permitting high speeds, and also a machine in which the necessity of piecing threads, if they are broken during spinning, is obviated.

The appended drawing shows a vertical section through one embodiment of the present invention 30 in operation. In said drawing 1 is the delivery roller, 2 a coacting top roller, 3 a drawn silver, 4 the silver sucking tube, 5 an air chamber, 6 guide vanes, 7 the stream guide pipe, and 8 a silver turned into a thread. 9, 10, and 11 are parts of 35 the drawing apparatus. 12 is the inlet for a fluid, 13 the holder for the silver sucking device, 14 a support for the holder, 15 the rotatable pot, 16 the cake, and 18 the edge of the thread guide tube.

According to this invention, the spinning machine is provided with silver sucking devices 4, 5, 6, and 7, and a pot 15 which have the characteristic feature of inducing the fluid in pipe 7 to 40 make a spiral, helical or like rotative movement 45 (hereafter called simply a rotative movement) 50

with respect to the drawing mechanism which comprises the front rollers 1 and 2 so that the spinning may be effected by sucking the silver 3 delivered from between the front rollers 1 and 2 into the sucking devices and discharging the same 5 into the rotating pot 15, giving said silver preliminary twist.

The silver sucking device is provided with guide vanes 6 opposite the lower end of the silver sucking tube 4, said vanes being also disposed around 10 the periphery of the upper end of guide tube 7. An open air chamber 5 is provided above the vanes 15 6 between the tubes 4 and 7. Unlike previously used apparatus, in this invention fluid is not poured into a silver sucking tube, but the compressed fluid is introduced into the air chamber 5 from the inlet 12 and is given a rotative movement upon passing through the guide vanes 6, so that the fluid will flow along the inner wall of the guide tube 7 by centrifugal force produced 20 therein, to cause rarefaction of the fluid at the center of said tube, whereby the air in the sucking tube 4 is sucked into tube 7, and accordingly the drawn silver 3 delivered from rollers 1 and 2 is automatically sucked into the tubes 4 and 7 and 25 is given a twist to form a thread 8, after which it is discharged into rotating pot 15 to be finely spun, and then reeled therein in the form of a cake 16.

The sucking devices 4, 5, 6, and 7 not only give 30 a desired rotative movement to the fluid in tube 7 due to the stream guiding vanes 6 in the path of the fluid, but also cause silver sucking action in the hopper-shaped chamber 5 at the upper part, so as to automatically suck said silver and conduct it into the rotating fluid in the tube 7 where 35 it is twisted into the condition of a partly formed thread, preventing the fibre from scattering about, and the silver is then discharged into the rotating pot 15 and spun, after which it is reeled along the inner wall of the pot in such a way as 40 to form a bundle or cake 16.

The drawing mechanism may be provided with 45 means (not shown) for stopping, when necessary, rotation of the middle rollers 9 and 10 and the back roller 11 with respect to the front rollers 1 and 2, thus stopping delivery of the silver 3 while removing a bundle or cake 16 of thread 50 from the pot 15.

Thus, as compared with the "Ring" spinning machines now in use, my novel machine is much 55 better adapted for high-speed spinning since the tension of the thread during spinning is not only as uniform as possible, but also the thread during spinning is enveloped by the fluid 5 in the tube 7 which has the same rotating and advancing 55

movements as the thread during the latter's passage through the sucking devices. Moreover, the trouble of piecing threads, when broke, during spinning is obviated, resulting in a remarkable improvement in efficiency. If a thread is broken during spinning, there is no necessity of piecing or joining it, since the sliver 3 is spun while enveloped in the rotating fluid 5' in the guide tube 7, which fluid travels in the same direction as the sliver, and thus there is no possibility of scattering or separating the fibres. This not only reduces the chance of breaking the thread, but also performs the spinning operation with substantially uniform tensile strength.

16 The tension applied to the spun thread is chiefly due to the action of the fluid and the centrifugal force of the rotating thread extending from mouth 18 at the lower end of the sucking device to the interior of the pot or bundle. The former may readily be kept constant easily, while the latter is gradually decreased with the change of the inner diameter of the bundle, but may be kept constant by a corresponding increase in the rotation of the pot 15. Thus in my machine, as the spinning action is made in a fluid having the same rotating and advancing movements as the thread, my machine has decided advantages over the "Ring" spinning machines, as it considerably diminishes the chances of breaking a thread, and prevents the scattering of the fibres.

I claim:

1. In a high speed spinning machine having a sliver drawing mechanism and having a sliver sucking device and having a rotatable pot; means for introducing fluid into said sucking device; and means in the sucking device for imparting to the fluid therein rotating and advancing movements whereby said fluid will envelop the sliver and cause initial twisting of the sliver within the sucking device.

2. In a machine as set forth in claim 1, said

imparting means comprising fluid directing vanes in the sucking device.

3. In combination with a machine as set forth in claim 1, means for stopping the drawing mechanism to interrupt the delivery of the sliver to the sucking device.

4. In a high speed spinning machine having a sliver drawing mechanism and having a sliver sucking device and having a rotatable pot; means for introducing fluid under pressure into said sucking device; and means in the sucking device for centrifugalizing said fluid therein while imparting thereto an advancing movement; whereby said fluid will envelop the sliver and cause initial twisting of the sliver within the sucking device.

5. In a machine as set forth in claim 4, said imparting means comprising fluid directing vanes in the sucking device.

6. In combination with a machine as set forth in claim 4, means for stopping the drawing mechanism to interrupt the delivery of the sliver to the sucking device.

7. In a high speed spinning machine having a sliver drawing mechanism and having a sliver sucking device and having a rotatable pot; means for introducing fluid under pressure into said sucking devices; and means in the sucking devices for imparting to the fluid therein a helical movement causing rarefaction of the air at the center of the sucking device; said fluid enveloping the sliver and causing initial twisting of the sliver within the sucking device.

8. In a machine as set forth in claim 7, said imparting means comprising fluid directing vanes in the sucking device.

9. In combination with a machine as set forth in claim 7, means for stopping the drawing mechanism to interrupt the delivery of the sliver to the sucking device.

EIZABURO NEGISHI.
